UNITED STATES PATENT OFFICE

ARTHUR A. GROTHE, OF OAK PARK, ILLINOIS, ASSIGNOR TO WILLIAM J. CAMERON, OF CHICAGO, ILLINOIS

SAFETY RAZOR MOTOR STRUCTURE

Application filed November 18, 1929. Serial No. 407,831.

My present invention relates generically to razors of the safety type, and it has particular reference to a structure of this character that is operated through the medium of an electric current.

A variety of devices have been heretofore designed to automatically operate a safety razor some of which have proven more or less successful from a commercial stand-point, but many of which have been objectionable because of certain inherent defects. Some of the prior structures have been designed especially for use with direct current, while others will function only with an alternating current. The automatic safety razor which I have produced is adapted to be operated by either the direct or the alternating current.

In my present device I have provided elements that are operated electrically to set up a vibration within the handle of the razor so as to give a slight side-to-side movement to the latter and thereby impart a slight longitudinal movement to the cutting blade. While these elements are necessarily of small dimensions in order to house them within the constricted interior of the razor handle they are nevertheless sturdy and simple in construction, and the arrangement thereof is such that the structure is so compact that it may be readily stored within a handle of relatively small diameter. Furthermore, the construction and arrangement of the actuating parts is such that it is easy to insert them in or remove them from the handle.

I prefer to carry out my invention and to accomplish the objects thereof in substantially the manner hereinafter fully described, and as more particularly pointed out in the appended claims, reference being herein made to the accompanying drawings that form a part of this specification.

In the drawings:

Figure 1 is a view in perspective showing my improved electrically operated safety razor.

Figure 2 is a view in longitudinal elevation showing the interior and the arrangement of the parts, the casing or handle portion being in section.

Figure 3 is a longitudinal view of the interior parts looking at the same from the side opposite that of Figure 2.

Figure 4 is a view, also in longitudinal elevation, of the parts shown in Figures 2 and 3 and viewed at a right angle to said figures.

Figure 5 is a transverse section taken on line 5—5 of Figure 3 and looking in the direction of the arrows.

Figure 6 is a fragmentary view of the base portion of the parts showing the delayed break of one of the contacts.

Figure 7 is a detail view showing the method or system of wiring.

Figure 8 is a schematic lay-out of the electrical circuit and associated mechanical parts.

The drawings are to be understood as being more or less schematic for the purpose of illustrating a typical or preferred form in which my invention may be made, and in said drawings I have employed similar reference characters to designate like parts wherever the same appear throughout the several views.

The structure which I have devised comprises a hollow cylindrical-shaped handle 10, the ends of which are closed by the bottom plug 11 and a top plug 12 that preferably screw into the ends of the handle. The top plug has a conical-shaped cap 13 that surrounds a post (not shown), and upon the outer end of the post within the cap 13 means are provided for readily attaching and detaching the head of the razor. This head consists of the guard 14 and the clamping member 15 between which a double or two-edged razor-blade is secured by drawing the parts together which flexes the blade transversely in the manner of a well-known type of safety razor.

The hollow handle 10 provides a housing or casing that encloses the electrical parts for operating the razor by causing a vibration which is transmitted to the head through the post that is rigid within the top plug 12. Imbedded in the top plug 12 are two metal rods 16 and 17 that are arranged parallel to each other and form the cores for the two windings 18 and 19 respectively that surround said cores throughout the greater por-

tion of the lengths of the latter, and in order to protect these windings they are covered with a strip of paper or other insulating material 20 and 21 as shown in Figure 2. At 5 their ends opposite the plug 12 the cores 16 and 17 enter recesses or sockets 22 and 23 that are formed in the adjacent face of an insulating base 24 and are secured therein by the flat headed bolts or screws 25 and 26 that 10 pass through the base in the manner shown. The hollow wall 10 and the plugs 11 and 12 of the housing or handle are preferably made of a suitable insulating material and when the coils and base are inserted into the handle the face of the base 24 will abut the inner 15 face of the lower plug 11. Also mounted upon the base 24 and extending longitudinally parallel with the cores 16 and 17 is an armature 27 the end of which adjacent the base is 20 reduced and flattened to provide a stiff spring neck 28 to permit a vibratory movement of the armature when attracted towards the cores. The tension of this spring portion 28 is sufficient to permit vibratory movement of 25 the armature and this tension may be such that actual impact against the pole ends of the cores or other adjacent structure is prevented. Beyond the neck 28 the end of the armature is enlarged in the form of a head 30 29 that is firmly embedded in the base 25, thus supporting the armature with its opposite end free to vibrate in the desired manner as hereinafter described.

The opposite or vibratory end of the armature 27 is slightly reduced and flattened as 35 shown at 30 and its end nearest the plug 12 is bent substantially L-shaped to provide an arm 31 that extends laterally between the adjacent exposed portions or pole ends of the cores 16 and 17 between the plug 12 and the adjacent ends of the wiring 18 and 19.

In its vibratory movement the armature 27 has its lateral arm 31 attracted toward the exposed portions or poles of the cores 16 and 45 17 but it is prevented from actually contacting with these poles by means of small soft rubber buffers or stops 32 that are mounted in the irregular shaped brackets 33 that are secured to the opposite surfaces of the cores 50 16 and 17 respectively. The buffers absorb a portion of the shock incident to the attraction of the armature toward the poles or cores when said armature is being vibrated, and as said brackets and cores are anchored upon 55 the plug 12 adjacent the post which carries the head the vibrations are thus transmitted to the post and head and they are caused to vibrate trans-axially. The armature is adapted to freely vibrate between the poles 60 without contracting the same, and the buffers act as a cushion under extraordinary conditions should the vibratory strokes of the armature inadvertently become lengthened and they thus absorb both the shock and noise 65 that would be incident to actual contact be-

tween the parts. Such vibratory movement is of course transmitted to the cutting edge of the razor blade, so that when the razor is moved upon the flesh in the usual manner of operating a safety razor such vibratory movement will cause a sheering or slicing cut and thereby materially assist in the operation of shaving. In other words the action of the blade upon the individual hairs that are to be removed is the well-known "slide-stroke" or oblique cut used by professional barbers and which is very effective in the operation of shaving.

The current may be from any suitable source of electrical supply and it is conveyed to the handle of the razor by a flexible conductor element 34 the adjacent end of which is provided with a socket member 35 adapted to be inserted into the central opening 36 made in the bottom plug 11 of the handle. Suitable terminals 37 and 38 are embodied in the plug and extend into the opening 36 with their ends back of the plane of the outer face of said plug, and coact with the counter-part portions of the socket member 25 when the latter is in position. The inner portions of the terminals, which are preferably wire, are given L-shaped bends 39 as seen at Fig. 4 and then pass out of the base 24 within the handle and adjacent the respective coils.

Extending from the base 25, preferably upon each side of the armature 27 are stubs 39 and 40 the outer portions of which are reduced as at 41 and 42 and at their ends they are provided with contacts 43 and 44 respectively in the shape of small disks or blocks. These contacts cooperate with similar opposing contacts 45 and 46 upon diametrically opposite sides of the armature 27 and said contacts 43 and 44 are normally urged towards the armature by the reduced portions 41 and 42 which are of the yielding spring character. The contacts 43, 44, 45, and 46 are magnetized so that the pairs remain in contact until one of the springs overcomes the magnetic force and moves one of a pair of elements out of contact. The spring 42 for example is slightly stronger than spring 41 and when the armature 27 is moved in the direction to break the circuit between the contacts 44 and 46 these blocks will hold to each other until the spring 42 overcomes the magnetic force and the contacts 44 and 46 will be separated causing a delayed "break". When, however, the armature moves in the opposite direction the two pairs of contacts remain in engagement.

What I claim is:—

1. A device of the kind described comprising a hollow handle, a front plug and a rear plug closing and sealing said handle, a pair of spaced electromagnet cores anchored on one of said plugs and provided with energizing windings, a vibratory armature inter-

mediate the axial planes of said cores and having a spring end for supporting the same, means on the free end of said armature adapted to be attracted towards the respective core pole ends when said cores are energized whereby to vibrate said handle, and a tool post anchored in said front plug independent of said cores and armature and vibrated solely by said handle.

2. A device of the kind described comprising a hollow handle, front and rear plugs closing and sealing the ends thereof, a pair of spaced electromagnet cores anchored on one of said plugs and provided with energizing windings, an insulating base to which the opposite ends of said cores are secured, a vibratory armature intermediate the axial planes of said cores and one end of which is attracted towards the pole ends of the cores when the latter are energized whereby to vibrate said handle, a spring connecting the opposite end of said armature to said base, and a tool post anchored in said front plug independent of said cores and armature and vibrated solely by said handle.

3. A device of the kind described comprising a hollow handle, front and rear plugs closing the ends thereof, a pair of spaced electromagnet cores anchored on said front plug and provided with energizing windings, a vibratory armature intermediate the axial planes of said cores and anchored at its end opposite the anchored ends of said cores whereby to vibrate said handle, buffers on the pole ends of said cores adapted to be struck by said armature when the latter is vibrated, and a tool post anchored in said front plug and vibrated solely by said handle.

4. A device of the kind described comprising a hollow handle, electromagnet cores mounted therein, and provided with energizing windings, a vibratory armature coacting with the pole ends of said cores, spring contacts upon opposite sides of said armature, one of said contacts being magnetized whereby to cause a delayed break in a circuit passing therethrough, and means for mounting a tool upon an end of said handle.

5. A device of the kind described comprising a hollow handle electromagnet mechanism within said handle and including an impactless freely vibrating armature, yieldable spring contacts normally engaged with said armature, one of said contacts being magnetized whereby to cause a delayed break in a circuit passing therethrough, and means for mounting a tool upon an end of said handle.

6. A device of the kind described comprising a suitable support, a removable front head therefor, a base in the other end of said support, a pair of cores extending between said head and base and anchored on said head to permit removal from the support with the head and base, energizing windings on

said cores, an armature having a portion freely vibratory between the pole ends of said cores adjacent the head, a spring supporting said armature from said base, said spring having sufficient tension to retard the vibratory movement of said armature, and means for securing a tool to the front head whereby a tool mounted in said means is subject to the vibratory movement of the structure.

7. A device of the kind described comprising a suitable support, a removable front head therefor, a base in the other end of said support, a pair of cores extending between said head and base and anchored on said head and base, energizing windings on said cores, buffers on the pole ends of said cores, a yieldably mounted armature carried by said base and freely vibratory between said buffers when the pole ends of said cores are energized, the yieldability of said armature being sufficient to prevent impacting any adjacent structure whereby to vibrate said support and parts carried thereby, and means for securing a tool to the front head whereby a tool mounted in said means is subject to the vibratory movement of the support.

Signed at Chicago, Cook County, Illinois, the 22nd day of August, 1929.
